(57) **CLAIM**

The ornamental design for a mobile phone with transitional graphical user interface, as shown and described.

DESCRIPTION

FIG. 1 shows a first state of a mobile phone with transitional graphical user interface;

FIG. 2 shows a second state thereof;

FIG. 3 shows a third state thereof;

FIG. 4 shows a fourth state thereof; and,

FIG. 5 shows a fifth state thereof.

The subject matter in this patent includes a process or period of the claimed design. This process or period forms no part of the claimed design.

The broken line showing of the mobile phone is for the purpose of illustrating environmental structure and forms no part of the claimed design.

1 Claim, 5 Drawing Sheets

FIG. 1

FIG. 2

FIG. 3

FIG. 4

FIG. 5
